(57) **CLAIM**

The ornamental design for a display assembly, as shown and described.

DESCRIPTION

FIG. 1 shows a top left-side front perspective view of the display assembly of our new design in an environment of a robot vehicle;

FIG. 2 shows a top right-side rear perspective view of the display assembly of our new design in an environment of a robot vehicle;

FIG. 3 shows a front elevation view of the display assembly of our new design in an environment of a robot vehicle;

FIG. 4 shows a right-side elevation view of the display assembly of our new design in an environment of a robot vehicle;

FIG. 5 shows a rear elevation view of the display assembly of our new design opposite that of FIG. 3 in an environment of a robot vehicle;

FIG. 6 shows a left-side elevation view of the display assembly of our new design opposite that of FIG. 4 in an environment of a robot vehicle;

FIG. 7 shows a top plan view of the display assembly of our new design in an environment of a robot vehicle;

FIG. 8 shows a bottom left-side front perspective view of the display assembly of our new design in an environment of a robot vehicle;

FIG. 9 shows a front elevation view of a second embodiment of the display assembly of our new design in an environment of a robot vehicle, the second embodiment showing a black

(Continued)

surface color of a forward-facing portion of lower sides and a bottom portion of a display screen surround member; FIG. 10 shows a right-side elevation view of the second embodiment of the display assembly of our new design in an environment of a robot vehicle, the second embodiment showing the black surface color of the forward-facing portion of lower sides and the bottom portion of the display screen surround member;

FIG. 11 shows a left-side elevation view of the second embodiment of the display assembly of our new design opposite that of FIG. 10 in an environment of a robot vehicle, the second embodiment showing the black surface color of the forward-facing portion of lower sides and the bottom portion of the display screen surround member; FIG. 12 shows a top left-side front perspective view of the second embodiment of the display assembly of our new design in an environment of a robot vehicle, the second embodiment showing the black surface color of the forward-

facing portion of lower sides and the bottom portion of the display screen surround member;

FIG. 13 shows a top right-side front perspective view of the second embodiment of the display assembly of our new design in an environment of a robot vehicle, the second embodiment showing the black surface color of the forward-facing portion of lower sides and the bottom portion of the display screen surround member; and,

FIG. 14 shows a bottom left-side front perspective view of the second embodiment of the display assembly of our new design in an environment of a robot vehicle, the second embodiment showing the black surface color of the forward-facing portion of lower sides and the bottom portion of the display screen surround member.

The broken or evenly-dashed lines are included to show structure of the display assembly in the drawings that form no part of the claimed design.
